CLAIM

The ornamental design for a coffee maker, as shown and described.

DESCRIPTION

FIG. 1 is a perspective view of a coffee maker according to the claimed design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the article shown in broken line form no part of the claimed design.

(Continued)

The dash-dot lines represent the bounds of the claimed design and form no part thereof.

1 Claim, 7 Drawing Sheets

Related U.S. Application Data

continuation-in-part of application No. 29/708,553, filed on Oct. 8, 2019, now Pat. No. Des. 894,660, which is a division of application No. 29/687,098, filed on Apr. 10, 2019, now Pat. No. Des. 867,047, which is a division of application No. 29/639,760, filed on Mar. 8, 2018, now Pat. No. Des. 849,464, which is a continuation-in-part of application No. 29/618,139, filed on Sep. 19, 2017, now abandoned.
